(57) **CLAIM**

The ornamental design for the “changing table”, as shown and described.

DESCRIPTION

FIG. 1 is a perspective view of the “changing table”, showing my new design;

FIG. 2 is a front elevation view thereof;

FIG. 3 is a rear elevation view thereof showing a bath applied thereto;

FIG. 4 is a side elevation view thereof showing a bath applied thereto;

FIG. 5 is another side elevation view thereof showing a bath applied thereto;

FIG. 6 is a top plan view thereof;

FIG. 7 is a bottom plan view thereof; and,

FIG. 8 is a perspective view of the table, displaying the bath. The broken lines are for environmental purposes only and form no part of the claimed design.
